COMBINED CLOSURE CAP AND BRUSH
DISPENSER

Charles E. Main, Akron, Ohio

Application April 16, 1949, Serial No. 88,006

3 Claims. (Cl. 15—138)

1

This invention relates to a container with closure and dispensing means, and more particularly to an improved sealing closure and dispensing device equipped with a brush applicator and permanently affixed to a container, which device is especially adapted to be employed in the dispensing and brushing of the fluid or liquid contents of the container upon or over various materials, such as cloth, leather, etc., to clean and/or to polish such materials, or for cosmetic treatments.

An object of the present invention is to provide a combined sealing closure and dispensing device of the brush applicator type for containers which device, exclusive of the brush applicator and an internal compressible packing element, shall be cheap and easy to produce and lends itself to being made in two pieces only, each of molded organic thermoplastic material with relatively thick wall sections, and having threaded connection one with the other for relative rotational movement.

Another object of the invention is to provide a combined sealing closure and dispensing device of the type indicated which will include an inner sealing closure member and an outer turnable cap wherein sealing of the container against loss of its fluid contents or control of the flow of the liquid out of the container will be obtained by means of complementary interfitting sealing portions carried by said closure and cap members and which will be brought into either sealed or opened positions when the brush applicator cap is manually turned in an appropriate direction on the inner closure member.

Another object of the invention is to provide a combined sealing closure and dispensing device of the type indicated which will include an inner sealing closure carrying a turnable outer cap formed with conical liquid discharge means for cooperation with a conical liquid feeding projection carried by the inner sealing closure wherein the latter will be permanently sealed to the container head, and sealing or control of the flow of liquid contents from the container through said projection and said conical discharge means to the brush applicator may be obtained upon appropriate turning of said cap on the inner closure member of the device.

To these ends, the device of the invention comprises a combined sealing closure and dispenser of the brush applicator type which in the embodiment selected for illustration is composed of two members having threaded connection one with the other, each of said members being formed as a relatively thick walled generally cup-like molded body of organic thermoplastic material. The inner molded plastic member forms the primary sealing closure for the container. The container is filled with the desired fluid before being

10 capped, after which the inner sealing closure is placed over the container mouth and reformed and shaped in a heated state to a portion of the container neck and around and under one or 15 more beads thereon under conditions of axial and radial pressure carried out in a manner to cause the softened organic thermoplastic material to be forced against and ironed over the outer side walls of the container neck into intimate conformity with the exterior finish of such walls and bead portions. The brush applicator element is carried by the outer molded plastic member or cap. There is further provided a 20 combined valve and sealing means which in its preferred form is composed of conical outflow passage means in said cap adapted to be adjusted into different opened and closed positions by appropriate turning of the associated cap for controlling the feed of the fluid or liquid contents flowing out from the container to the brush applicator element from a discharge vent or aperture in the side wall portion of a hollow conical projection disposed in cooperative sealing and valving relationship with side surface portions of 25 said conical outflow passage means and formed integral with the top of the inner molded sealing closure of the device.

Illustrative embodiments of the invention are described in the following specification and illustrated in the accompanying drawings, in which

30 Fig. 1 is a side elevation of a container equipped with a combined sealing closure and dispensing means of the brush applicator type constructed in accordance with this invention;

35 Fig. 2 is an enlarged fragmentary vertical sectional view of a container head sealed with a combined closure and dispensing device in accordance with this invention, and showing the valve parts in closed or sealed position;

40 Fig. 3 is a sectional view similar to that of Fig. 2 but showing the valve parts in unsealed or open position for dispensing the fluid contents to the brush applicator when the container is inverted;

45 Fig. 4 is an enlarged top plan view of the combined sealing closure and dispensing device shown in Fig. 1;

50 Fig. 5 is a horizontal section taken on the line 5—5 of Fig. 2 showing the hexagonal external rim end of the container head at the mouth opening in interlocked relationship with the twelve sided inner side wall extremities of the bottom recess of the combined sealing closure and dispensing device for preventing turning of the inner member upon the container neck;

55 Fig. 6 is an enlarged fragmentary vertical sectional view, with parts in elevation, of a container head, a molded preheated thermoplastic inner fitment of the combined closure and dispensing device of Figs. 2 and 3 loosely fitted over the upper end and beads of the container head, and

a seal forming machine illustrating the parts at the start of a roll-on sealing operation:

Fig. 7 illustrates diagrammatically a container head having a screw-threaded neck and showing a molded thermoplastic closure cap at the completion of the roll-on sealing operation onto the container;

Fig. 8 shows in vertical section a modified form of thick walled thermoplastic dispensing closure cap applied to a container in accordance with the invention; the cap including a compressible high stretch plastic stopper element for sealing the container opening;

Fig. 9 is a greatly enlarged fragmentary sectional view, with the parts in elevation, of a container head provided with an external bead having a reentrant under surface, a molded pre-heated thick walled thermoplastic closure cap loosely fitted over the mouth opening of the head and encompassing the aforesaid bead, and a seal forming machine element depicted in dot and dash outline in proper position to begin a roll-on sealing operation to reform the lower skirt portion of the closure cap, in a heated state, against and under the reentrant under surface of the bead; and

Fig. 10 is a greatly enlarged sectional view, in elevation, of a container head with two beads, each of substantially square cross-section, sealed with a closure cap having a skirt portion reformed in direct contact with under sides of both beads and with the intervening exterior surfaces on the container.

In Figs. 1 to 6 inclusive, reference numeral 10 designates a glass receptacle or rigid container for storing, transporting and dispensing various liquids or fluids such as, for example, liquid cosmetic preparations, polishing, or cleaning fluids, etc. The container 10 has an upstanding head in the form of a tubular neck 12 with rounded axially spaced external beads 13 and 14 disposed one above the other and separated by an external concaved wall surface 15. The neck 12 has an upwardly open mouth passage 16 through which the fluid contents flow when the container is inverted, and the outer rim of the container head 12 at the upper end about the mouth opening 16 to the container is formed with a series of circumscribing flats to provide a hexagonal lip 18, as shown in Figs. 2, 5 and 6.

In the form shown in Figs. 1, 2, 3 and 6, the combined sealing closure and dispensing device for the container comprises inner and outer threadingly connected members 20 and 21 respectively each formed as molded generally cup-like bodies of organic thermoplastic material having relatively thick top and side walls. The organic thermoplastic materials of which the plastic members 20 and 21 may be formed may vary in nature and have different degrees of hardness and flow characteristics, so that different organic thermoplastic materials may be used to produce these relatively thick walled molded bodies having similar nature or like properties for application to the container 10 in accordance with the invention. Preferably, the molded plastic members 20 and 21 are formed of cellulose acetate butyrate which is an organic thermoplastic material known in the plastic molding art under the trade name of "Tennite II" and manufactured by the Tennessee Eastman Corporation, Kingsport, Tennessee. Molded articles formed from cellulose acetate butyrate have the following general characteristics: excellent dimensional stability, high resistance to shrinkage and dis-

tortion under varying conditions of temperature and humidity, low moisture absorption, high impact strength, and improved surface finish.

The inner member 20 which constitutes the sealing closure member for the container 10 has a generally flat top 22 with an upstanding axially disposed hollow conical projection 23 the side wall of which is formed with a fluid discharge vent or aperture 24 therethrough. The size of the aperture 24 may vary to suit the nature and viscosity of the fluid to be dispensed from the container 10. Thus, for volatile fluids one or more very fine or minute apertures will be used whereas when viscous liquids are to be dispensed from the container an aperture of substantial size will be utilized. As illustrated, the closure member 20 is formed with an externally threaded upper portion 25 and a lower relatively thick walled depending annular skirt portion 26 defining a cylindrical open bottomed chamber extending axially inwardly from the bottom of the closure member and terminating in an annular end wall with an axially disposed feed opening. The inner wall surfaces of this chamber at the innermost end thereof adjoining the back or end wall are formed with a series of circumscribing flats to provide a twelve-sided socket 29 which will have interlocking engagement with the hexagonal lip 18 for restraining the closure member 20 from rotation about the container head 12 when the closure member is secured permanently thereto.

Fixed within the closure member 20 against the top wall of the cylindrical chamber is a sealing ring 30 of any suitable material, for example, cork, synthetic rubber, or other resilient and compressible material the character of which will be unaffected by the fluid contents of the container.

According to this invention, and as shown in Fig. 6, the closure member 20, after being pre-heated to a temperature above its softening point, is placed while in a heated state over the container head with the depending skirt 26 completely embracing the beads 13 and 14 and extending for a substantial distance below the lower bead 13. When thus positioned, the hexagonal lip 18 will have interlocking connection with the twelve-sided socket 29 provided interiorly of the open bottomed chamber of the closure member 20. While still in a heated state, the closure member 20 is forced downwardly by a pressure block 31 to compress the sealing ring 30, and while the closure member 20 is thus held by the pressure block 31 the skirt portion 26 is firmly forced radially inwardly against the container neck and the softened heated thermoplastic material of the skirt 26 deformed, reformed and forced into direct contact and tight sealing relationship with the exterior concaved wall surface 15 and adjoining portions of the beads 13 and 14 bordering thereto by a suitable roll-on tool, for example, the rotatable spinning disk 33, the arrangement of which will be more fully described hereinafter, and arranged to be thrust in the direction indicated by the arrow against the outer portions of the closure skirt 26 to be reformed.

The pressure block 31 and the spinning disk 33 may form elements in a known form of bottle capping apparatus such as that disclosed in U. S. Patent No. 1,674,266 to Sharp. The substitution of the pressure block 31 here shown for the one shown in the above mentioned Sharp patent does not change the mode of operation of that apparatus when used in accordance with the present invention. As illustrated in Fig. 6, the pressure

block 31 is suitably affixed to a vertically movable post 35 and the pressure block has a depending annular metal rim portion 36 which defines a relatively shallow cup-like recess 37. The pressure block 31 is provided with a central cylindrical bore 38 of suitable size for receiving the conical projection 23 of the closure member 20, the annular rim 36 serving to effect centering of the closure member 20 with respect to the pressure block 31 during the capping operation. The lower end of the rim portion 36 of the pressure block preferably projects down over the top edge portion of the closure member 20 when the recess 37 is fully seated upon the top of the closure member, in which case, the conical projection 23 is housed wholly within the central hole 38 of the pressure block 31.

In the course of the capping and roll-on operations the closure member 20 is forced downwardly by the post 35 and the pressure member 31 to compress the sealing ring 30 and hold it in a compressed state in tight sealing engagement with the upper end opening of the container head 12.

To carry out the spinning or "roll-on" operation, as represented in Fig. 6, the rotary spinning disk 33 is there shown as being attached to a shaft 45 rotatably mounted in the outer end of an arm 46 which may be suitably arranged for lateral movement towards and from the container head 12 such as, for example, in the apparatus disclosed in the aforesaid Sharp patent. Shaft 45 is yieldingly urged upwardly by a spring 47 which bears at one end upon a nut 48 attached to the upper end of the shaft and at its other end upon a collar 50 resting upon the outer end of arm 46. The arrangement here shown is such that the same mount for the spinning disk can be used for rolling the closure member 20 onto a beaded container neck, as shown in Fig. 6, or a closure member 20' upon a threaded container neck 12' as shown in Fig. 7 such as is provided on screw top containers, or a closure 104 of thermoplastic material into full locking engagement with a pair of spaced beads 102 and 103 of square cross-section carried exteriorly by a container neck 101, such closure modifications and capping and sealing operations in connection therewith according to the invention being more fully described in greater detail hereinafter.

While there has been shown in Figs. 6 and 7 a single spinning disk element for rolling on and reforming the closure skirt around the container neck, it is to be understood that in practice, it is preferred to use a plurality of such disks spaced at equal angular intervals around the container neck and having planetary movement thereabout.

Returning now to the specific structure of the combined closure and dispensing device shown in Figs. 1 to 6 inclusive, the outer plastic member 21 thereof, as previously stated, resembles an inverted cup-like body of molded organic thermoplastic material having a relatively thick flat top wall 60 with sloping side portions contiguous therewith and a depending relatively thick annular skirt portion 63 defining an inwardly directed deep open bottom recess 64. The inner wall portion of said recess 64 is provided with internal screw threads 65 complementary to the threads 25 of the inner closure member for threading connection and rotatably mounting of the outer member 21 thereto.

Secured to the outer cap member 21 is a brush applicator, the bristles 66 of which are arranged in two parallel rows extending transversely across

the end wall of the cap member 21. The bristle tufts are arranged in clusters, each having twelve or more bristles, and the base portions of the tufts forming each cluster are firmly anchored in suitable apertures provided through the end wall of the cap member 21. The outer cap member 21 is provided with an axially disposed restricted outlet or discharge opening 70 in its end wall. As shown in Fig. 3, the outlet 70 is constricted forwardly beyond its mid-portion and the diameter of the outlet tapers in both directions axially towards the constricted part of the outlet. Thus, the outlet 70 resembles in longitudinal section a double coned opening somewhat like an hour-glass. The conical wall surface of the inner end of the outlet 70 is so shaped as to seat against the conical outer surface of the projection 23 of the closure member 20 to close and seal the restricted outlet of the cap member 21 when the cap is in a retracted closed position, and to provide for a fluid control action between the conical surfaces 71 and 72 to regulate the feeding of the container contents discharged from said side aperture 24 to the brush bristles 66 when the cap member 21 is turned into different extended open positions. When it is desired to dispense the contents of the container 10, the cap 21 is unscrewed sufficiently to move the outlet opening 70 out of engagement with the conical projection 23, as shown in Fig. 3. By inverting the rigid container 10, the fluid contents of the container will flow through the aperture or vent 24 in the side of the conical projection 23 and thence through the conical feed passage thus provided to the outside of the cap member 20 to wet a group of four clusters of bristle tufts in the immediate proximity to the marginal borders of the conical feed hole. The fluid will be transferred to the remaining groups of bristles upon brushing an object with the applicator. The conical side surface 71 of the projection 23 has a regulatable and valving action with the inner conical surfaces 72 of the conical feed opening 70 for fluid control when the cap 21 is turned about the closure member 20 into various extended open liquid dispensing positions. A fluid tight seal is provided by the cap 21 when it is screwed down on the closure member 20 into a closed or sealed position to effect firm sealing engagement of the complementary conical surfaces 71 and 72 of the feed opening 70 and the projection 23 respectively.

The inner conical valving and sealing surface 72 of the cap 21 extends more deeply into the back wall of the cap and also well beyond the middle of its end wall thickness as shown in Figs. 2 and 3, thus providing a feed opening 70 having entrance and exit end openings of different size conical surfaces.

In Fig. 7, the thermoplastic closure skirt 26, in a heated state, is affixed to the container 10' by being deformed radially by the rotatable spinning or roll-on disk 33' and the heated material reformed around and locked into the threads on the container neck 12'. Thus, in the reforming operation illustrated in Figure 7, the spinning disk 33' is pressed radially inwardly against the closure skirt 26' and relative rotation effected between the container 10' and the spinning disk 33', in the course of which operation the disk 33' will follow the groove of the thread 51 of the container neck and move downwardly against the compression of the spring 47', as indicated in dot and dash outline in Fig. 7. As the disk 33' rolls around the container neck 12' it presses the

softened thermoplastic material of the closure skirt 26' into the groove of the thread 51 progressively from the upper to the lower end of the thread. This results in spinning upon the plastic closure skirt of a thread in tight conformity with the threads of the container to form a fluid tight primary seal thereto and which will result due to the "spring-back" tendency of reformed thermoplastic material of the closure skirt and the resiliency of the sealing gasket 30' when the pressure block 31' is raised to remove its pressure upon the closure member 20'.

In the modification shown in Fig. 8 the glass container 80 has affixed thereto a dispensing cap 81 formed of a molded thermoplastic material with a depending flange 82 rolled on while in a heated state by a spinning disk 33''' and interlocked under an exterior lip 83 formed at the top of the container neck. The cap 81 carries an upstanding tubular boss 84 through which is inserted the shank 85 of a removable pin stopper 86. Closing the neck discharge opening of the container is a tubular stopper 87 made of a high stretch plastic, such as polyethylene, and suitably attached at its upper end as by a layer of cement 88 to the under side of the cap 81 in such relation thereto that the projecting shank 85 of the pin stopper 86 will extend into and completely close the axial passage through the stopper 87. The outer peripheral sides of the stopper 87 preferably are formed with a slight taper from top to bottom, for example, a one degree taper; the outer diameter at the small end being made several thousandths of an inch larger than the inside diameter of the container discharge opening to make a tight push fit therein.

In Fig. 9 is shown another form of the invention wherein a molded thick-walled thermoplastic sealing cap 90 with its internal packing ring 30''' is placed, while in a heated state, over the mouth opening of the neck 12''' of the glass container 10''''. In this instance, the intermediate portion of the container neck 12''' is formed with an external bead 91 having a reentrant undersurface 92, and the cap 90, after being applied over the neck 12''' in the manner just described, has its depending skirt 93 loosely fitted about the bead 91 so as to encompass the latter while the lower portion of the skirt 93 extends downwardly below the bottom of the bead 91 for a distance substantially equal to the radial width of the underside of the bead. Thus, sufficient thermoplastic material in the portion of the skirt 93 depending below the bead 91 will be assured for reforming and being ironed, in a heated state, against and under the reentrant undersurface of the bead 91, as indicated at 93' in dot and dash outline, by a suitable roll-on disk 33''' also indicated in dot and dash outline.

Fig. 10 shows still another modification of the invention in which the glass container 100 has its head or neck 101 formed with two circular beads 102 and 103 each of substantially square cross-section and spaced apart axially of the neck 101. The mouth opening of the neck 101 is shown sealed by the closure cap 104 of organic thermoplastic material and the compressible packing ring 107. The cap 104 has a relatively thick walled depending skirt 105, here shown at the completion of the roll-on sealing operation according to this invention, with the thermoplastic material of the heated skirt 105 being reformed and ironed under and in direct contact with the undersides of the beads 102 and 103 and also firmly against the intervening exterior finish surfaces

on the container neck 101 between both beads. Prior to the reforming operation the lower portion of the skirt 105 occupies the position indicated at 106 in dot and dash outline.

It will be observed in view of the foregoing description that the novel method of the present invention can be employed for affixing sealing closure caps to glass containers having one or more rounded beads spaced apart on the container neck as shown in Figs. 1 through 6, or to a container head having screw threads as shown in Fig. 7, or to a container head having an undercut flange with a negative "rake," or to a container head having one or more straight flanges as shown in Fig. 10. In each of the specific forms above described it is to be understood that a gasket ring 30, 30', 30''' or 107 of cork, rubber or other resilient and compressible material is provided interiorly of the sealing closure members 20, 21', 90 and 104 respectively and is held in a compressed state for sealing the upper end opening of the container head while the heated and softened skirt portion is spun or rolled on the container neck so that the reformed thermoplastic material constituting the skirt conforms closely to and is complementary of the opposed engaged portions of the external glass finish, beads, threads or flanges to acquire a firm grip on said parts after contraction, cooling and setting of the reformed organic thermoplastic material of said closure skirt.

As a specific example of a preferred embodiment of the invention, a hollow closure having a depending annular skirt is molded as a preformed fitment of cellulose acetate butyrate having the walls of its skirt portion approximately .050" to .070" in thickness. The skirt is rendered flowable and reformed during the roll-on operation under an externally applied side or lateral pressure of approximately 50 lbs. while at a heat of approximately 170° F. to 180° F. for several seconds.

During the roll-on and reforming operation, the sealing closure cap is subjected to pressure on top by the pressure block of approximately 250 lbs.

While I have described the thermoplastic thick walled dispensing and sealing closures and caps depicted in the above described forms of my invention as being made of cellulose acetate butyrate, it will be understood that for certain uses where the high impact and compressive strengths afforded by the cellulose acetate butyrate is of lesser importance than tensile strength, flexural strength and a lower percentage of elongation other plastics may be used for forming such molded fitments, such as cellulose acetate, which material because of its close resemblance to cellulose acetate butyrate in thermal, mechanical and chemical properties is virtually interchangeable therewith.

What is claimed is:

1. In a combined closure cap and brush dispenser attachment for a rigid container having an externally flanged discharge neck, and a multi-sided surface on the neck above said flanged part and proximate to the discharge opening of said neck, a closure member having an externally threaded upper body portion and a lower depending annular skirt adapted to encompass and be secured to a flanged container neck, said skirt defining an open bottomed chamber extending axially inwardly from the bottom of the closure member and terminating in an annular end wall 75 having an axially disposed feed opening, said

chamber being provided internally with a multi-sided side wall surface adjoining the end wall of said closure member adapted for coacting in an interlocking manner with the multi-sided surface on the container neck to restrain the closure member against rotation thereon when the closure member is normally positioned on said neck and secured thereto, an axial hollow conical projection upstanding from the top of said end wall communicating with the feed opening thereof and formed with a laterally extending dispensing aperture in its side wall, a cap having an axial internally threaded end recess adapted to detachably and adjustably engage the threaded upper body portion of said closure member for manual rotation thereon, and a brush comprising tufts of bristles carried by the end wall of said cap and projecting outwardly therefrom, said cap being provided with an axially disposed restricted outlet in its end wall, said outlet being constricted forwardly beyond its mid-portion and towards which constricted part the diameter of the outlet tapers in both directions axially to resemble in longitudinal section a double coned opening, the conical wall surface of the inner end of said outlet being shaped to seat against the conical outer surface of said projection of the closure member to close and seal the restricted outlet of the cap when the cap is in a retracted closed position, and to provide for fluid control action between said conical surfaces to regulate the feeding of the container contents from said side aperture of said projection to the brush when the cap is turned into an extended open position.

2. In a combined closure cap and brush dispenser attachment for rigid containers having an externally flanged discharge neck with a flat-sided head portion proximate to the discharge opening, a closure member having an externally threaded upper body portion and a lower depending annular skirt adapted to encompass and be secured to a flanged container neck, said skirt defining an open bottomed chamber extending axially inwardly from the bottom of the closure member and terminating in an annular end wall having an axially disposed feed opening, said chamber having its wall surfaces at the innermost end thereof adjoining the end wall formed with a series of circumscribing flats to interlock with the flat-sided head portion of said discharge neck and restrain the closure member from rotation thereon when the closure member is secured to said neck, an axial hollow conical projection upstanding from the top of said end wall communicating with the feed opening thereof and formed with a laterally extending dispensing aperture in its side wall, a cap having an axial internally threaded end recess adapted to detachably and adjustably engage the threaded upper body portion of said closure member for manual rotation thereon, and a brush comprising tufts of bristles carried by the end wall of said cap and projecting outwardly therefrom, said cap being provided with an axially disposed restricted outlet in its end wall, said outlet being constricted forwardly beyond its mid-portion and towards which constricted part the diameter of the outlet tapers in both directions axially to resemble in longitudinal section a double coned opening, the conical wall surface of the inner end of said outlet being shaped to seat against the conical outer surface of said projection of the closure member to close and seal the restricted outlet of the cap when the cap is in a retracted closed position, and to provide

for a fluid control action between said conical surfaces to regulate the feeding of the container contents from said side aperture of said projection to the brush when the cap is turned into an extended open position.

3. A container having a neck portion comprising a plurality of flat surfaces on the neck proximate to the discharge opening thereof and extending downwardly therefrom, an annular bead adjoining the lower extremities of said flat surfaces, a second annular bead below and spaced from the first bead, and an annular groove between said beads, in combination with a closure member of a molded plastic material having a cup-like thick-walled upper shell portion provided with an externally threaded body portion and a thin-walled lower depending annular skirt portion extending downwardly over both beaded portions of the neck and having an internal annular flange firmly interlocked with said groove of the neck permanently securing the closure member to the container against endwise movement on said neck, said shell portion having a top wall provided with a central fluid feed opening in communication with the discharge opening of the container neck, said shell having the inner periphery of its side walls formed with internal flat surfaces coacting with the flat surfaces on said neck in an interlocking fashion whereby said closure member is restrained from rotation on the neck, an annular gasket internally of said shell between the top wall thereof and the end of said container neck and encircling said fluid feed opening, an axially extending hollow conical projection upstanding from the top wall of said shell portion communicating with the feed opening thereof and formed with a laterally extending dispensing aperture in its side wall, a cap member having in its top wall an outlet opening coaxial with said conical projection and formed internally with a conical surface of corresponding inclination, said cap member also having an axially disposed recess extending inwardly from its bottom end and formed with internal threads coacting with the threads on said threaded body portion of the closure member whereby said cap member may be manually turned into positions for regulating the fluid flow from said dispensing aperture between the conical surfaces of said projection and said outlet opening respectively and for completely shutting off the fluid flow therebetween, and a brush comprising tufts of bristles secured in the end wall of said cap about the outlet opening thereof.
